UNITED STATES PATENT OFFICE.

FRANK BEVER AND JOHN A. LENTZ, OF EL DORADO, KANSAS.

AUTOMATIC RAILWAY MAIL-CRANE.

SPECIFICATION forming part of Letters Patent No. 592,075, dated October 19, 1897.

Application filed May 3, 1897. Serial No. 634,829. (No model.)

To all whom it may concern:

Be it known that we, FRANK BEVER and JOHN A. LENTZ, citizens of the United States, residing at El Dorado, in the county of Butler and State of Kansas, have invented certain new and useful Improvements in Automatic Railway Mail-Cranes; and we do declare the following to be a full, clear, and exact description of the invention, such as will enable others skilled in the art to which it appertains to make and use the same.

Our invention has relation to improvements in railway mail-cranes, and the object is to provide a simple, effective, and automatic device for delivering and receiving or "catching" a mail-bag from a moving train.

To these ends the novelty consists in the construction, combination, and arrangement of the same, as will be hereinafter more fully described, and particularly pointed out in the claims.

In the accompanying drawings the same reference-characters indicate the same parts of the invention.

Figure 1 is a perspective view of our improved railway mail-crane as it appears in operation. Fig. 2 is a similar view as it appears after one mail-bag has been delivered to the mail-car and another received or "caught" by the crane. Fig. 3 shows the position of the crane ready to receive the mail-bag for delivery to the moving mail-car, and Fig. 4 is a vertical section through the crane.

1 represents the circular base, fixed to the station-platform or any other suitable foundation. 2 represents a cylindrical tubular socket adjustably secured in said base by means of set-screws 3, forming a telescopic joint, whereby the socket can be vertically adjusted to correspond to the height of the mail-car.

4 represents a cylindrical shaft sliding freely in the socket, and it is provided with a vertical cylindrical head 5, having an annular shoulder 6, which abuts against a corresponding shoulder 7, formed by the horizontal end of the socket.

8 represents an inverted-U-shaped slot formed in the socket, and which engages a friction-roller 9, mounted on a screw-stud 10, projecting radially from the shaft 4, and when the crane is ready for operation this roller

rests in a slight retaining-groove 11 in the lower side of the upper end of the slot 8.

12 represents a fixed guide-bracket on the head 5, which receives a vertical rectangular bar 13, provided with the integral horizontal spring-arms 14, arranged parallel with each other and provided with integral retaining-fingers 15 on their outer ends, which detachably engage the usual straps on the opposite ends of the mail-pouch, as shown in Fig. 1.

16 represents an orifice in the side of the bar 13, which engages the pawl 17 on the thumb-lever 18, fixed in the guide-bracket 12 and which retains said bar in an elevated position after it has received the pouch, and when a new pouch is to be attached the thumb-lever is released from the orifice in the bar and the bar lowered, so that the pouch can be readily adjusted to the spring-arms by a person standing on the ground, and the bar raised until the lever engages the orifice in the bar to support it in the elevated position within reach of the "catcher" on the mail-car.

21 21 represent vertical brackets fixed to the head 5 on either side of the guide-bracket 12, and either one of these vertical brackets are adapted to receive the rectangular shank 80 22 of a downwardly-projecting arm 23, the lower end of which is formed with a rectangular socket 24, provided with horizontal parallel ribs 25, which engage the rectangular tongue 26 on the block 27, fixed on the vertical shaft 28, journaled in the socket 24, the lower end of said shaft being encompassed by a spiral spring 29 and a fixed washer 30, which serve to retain said shaft in the socket and at the same time prevent it from turning laterally by holding the tongue 26 in contact with the parallel ribs 25.

31 represents a horizontal fixed arm on the vertical shaft 28, and 32 represents a curved lever fulcrumed on the upper end of the shaft 95 on a bolt 33, and having its curved arms 34 and 35 extending in approximately the same vertical plane as the fixed arm 31. The lower arm 34 of the lever 32 is sprung inwardly to frictionally engage the contiguous side of the fixed arm 31 to hold the lever in a horizontal position with the upper arm 35 resting against the limit-lug 36, ready to receive the mail-pouch from the car, as shown in Fig. 1, and

when the pouch is delivered in a horizontal position between the open arms 35 and 31 the body of the pouch coming in contact with the curved arm 34 releases it from the fixed arm 31, thus allowing the lever 32 to fall by gravity and secure the pouch, as shown in Fig. 2.

When the crane is positioned as shown in Fig. 1, the usual catcher on the car engages the pouch suspended between the spring-arms 14 14, carrying it forward and turning the arms in the direction of the moving train, so that the straps of the pouch will freely slide off the ends of the arms, and this movement releases the roller 9 from the groove 11 and it strikes the inclined upper edge of the U-shaped slot 8, which causes the shaft 4 to fall by gravity and assume the position shown in Fig. 2, with the arms 14 14 extending parallel with the track.

Although we have specifically described the construction and relative arrangement of the several elements of our invention, we do not desire to be confined to the same, as such changes or modifications may be made as clearly fall within the scope of our invention without departing from the spirit thereof.

Having thus fully described our invention, what we claim as new and useful, and desire to secure by Letters Patent of the United States, is—

1. The base 1, the cylindrical tubular socket 2, adjustably secured in said base and provided with the inverted-U-shaped slot 8, in combination with the shaft 4 having a verti-

cal oscillating movement in said bracket and provided with the radial friction-roller 9 engaging said slot, the guide-bracket 12 fixed to the upper end of said shaft and provided with the thumb-lever 18 and the bar 13 having a vertical movement in said guide-bracket, and provided with the horizontal parallel spring-arms 14 14, and the retaining-orifice 16, substantially as shown and described.

2. The base 1, the tubular socket mounted in said base and provided with the U-shaped slot 8, the shaft 4 having an oscillating movement in said socket, and provided with the radially-mounted friction-roller 9, in combination with the brackets 21 21 fixed to the upper end of said shaft, and the detachable arm 23 formed with a socket 24 provided with the parallel ribs 25 25, the vertical shaft 28 adjustably secured in said socket and provided with the tongue 26, the horizontal arm 31, and the lug 36, the spiral spring 29 encompassing the lower end of said shaft, and the washer 30 fixed on the lower end of the shaft, and the curved lever 32 fulcrumed on the upper end of said shaft, and provided with the curved arms 34 35, substantially as shown and described.

In testimony whereof we hereunto affix our signatures in presence of two witnesses.

FRANK BEVER.
JOHN A. LENTZ.
